Patented Apr. 12, 1921.

Inventor:

Ernest A. Couturier

By H. G. Rockwell, Atty.

UNITED STATES PATENT OFFICE.

ERNST A. COUTURIER, OF LAPORTE, INDIANA.

DESIGN FOR A MOUTHPIECE FOR MUSICAL INSTRUMENTS.

57,511.

Specification for Design.

Patented Apr. 12, 1921.

Application filed May 3, 1919. Serial No. 294,594. Term of patent 14 years.

To all whom it may concern:

Be it known that I, ERNST A. COUTURIER, a citizen of the United States, residing at Laporte, in the county of Laporte and State of Indiana, have invented a new, original, and ornamental Design for Mouthpieces for Musical Instruments, of which the following is a specification, reference being had to

the accompanying drawing, forming part thereof.

The figure is a side elevation of the mouth piece embodying my new design.

I claim:

The ornamental design for a mouthpiece for a musical instrument as shown.

ERNST A. COUTURIER.
